[57] CLAIM

The ornamental design for a beverage dispenser cabinet, as shown and described.

DESCRIPTION

FIG. 1 is a front and right side perspective view of a beverage dispenser cabinet showing our new design; FIG. 2 is a left side view of the beverage dispenser cabinet design of FIG. 1;

FIG. 3 is a rear elevational view of the beverage dispenser cabinet design of FIG. 1;

FIG. 4 is a top plan view of the beverage dispenser cabinet of FIG. 1;

FIG. 5 is a front elevational view of the beverage dispenser cabinet of FIG. 1;

FIG. 6 is a bottom view of the beverage dispenser cabinet of FIG. 1;

FIG. 7 is a front and right side perspective view of a modification of our new beverage dispenser cabinet of FIG. 1; and

FIG. 8 is a front elevational view of the beverage dispenser cabinet of FIG. 7. The left side, rear, top, and bottom views respectively are similar to FIGS. 2-4 of the beverage dispenser cabinet of FIG. 1.

The broken line showing of wording is for illustrative purposes only and forms no part of the claimed design.
